United States Patent Office

Des. 184,989
Patented Apr. 28, 1959

184,989

DECANTER

Ernest L. Du Pree, New York, N.Y., assignor to Schenley Industries, Inc., New York, N.Y., a corporation of Delaware

Application October 27, 1958, Serial No. 53,157

Term of patent 14 years

(Cl. D58—8)

All sides of the bottle are the same except for the monogram portion.

I claim:

The ornamental design for a decanter, as shown and described.
